PNEUMATIC DISPATCH SIGNALING SYSTEM

Dott W. G. McClure, Pasadena, Calif., assignor to
 Consolidated Engineering Corporation, Pasadena, Calif., a corporation of California

Application December 13, 1944, Serial No. 568,036

4 Claims. (Cl. 243—36)

1

This invention relates to delivery systems such as the pneumatically-operated type in which a receptacle is sent through a delivery tube from a sending station to a receiving station. The principal object is to provide in cooperation with such systems a signaling means for indicating receipt at the delivery end.

There are in common use pneumatically-operated systems for sending a cylinder or other carrier through a delivery conduit or tube from a sending end to a receiving end. Such systems operate by the application of air pressure or vacuum into the tube on the receptacle, this pressure or vacuum being applied by the sender at the sending end until the carrier element is delivered at the receiving end. For this purpose, it is convenient and desirable for the operator at the sending end to know when the carrier is received at the receiving end. It has heretofore been difficult to arrange a signaling system which will signify the receipt of the carrier at the receiving end, due to the fact that the carrier is traveling so fast that it does not have time to make a prolonged contact with any part of the system such as would enable a good electrical signal to be transmitted to the sending end.

In accordance with my invention, I have arranged a device for enabling an electrical signal such as an annunciator buzzer to be actuated at the sending end from operation of a switch at the receiving end when the carrier is received. I have done this by the provision within the conveyor tube at the receiving end of an elongated flexible strip extending longitudinally of the conduit and depressed while the carrier is passing it. As this strip has considerable length, it remains depressed for an appreciable time while the carrier is passing and is thus enabled to operate a switch for this appreciable time, whereby the signal is given at the sending end for an appreciable duration.

According to a preferred feature of my invention, I construct the elongated strip in two parts, the initial part being a resilient flexible portion, and the remaining part extending for the major portion of the strip, being of a stiffer construction.

According to a further feature of my invention, the elongated strip may be adapted not only to operate the switch, but also to act as a brake for the carrier.

The foregoing and other features of my invention will be understood from the following detailed description and the accompanying drawing, of which:

2

Fig. 1 shows partially in section, the sending and receiving ends of a pneumatically-operated carrier conduit, the conduit being provided with a signaling system according to my invention;

5 Fig. 2 shows a cross-sectional view taken at line 2—2 of Fig. 1; and

Fig. 3 shows a carrier element adapted to be transmitted through the tube.

Referring to Fig. 1, the pneumatic system comprises the usual tube conduit 1 through which is adapted to be conveyed a carrier member 2 of the general cylindrical shape shown in Fig. 3. This is shown with a washer 2a to act as a seal against the conduit wall. The conduit has two ends 3 and 4 and the carrier member 2 is adapted to be conveyed from either end to the other by pneumatic pressure. There is provided for the end 3 of the conduit a cover member 6 provided with a rubber gasket 7; and the pneumatic conveying pressure is provided through a tube 5 attached through the cover 6. The arrangement is such that when the cover member is placed in position over the end of the conduit 3, air from tube 5 may be sent into the end 3, by operation of a suitable valve (not shown), and blown through the tubular conduit 1 and out the other end 4. For this purpose, the cover member 6 at end 4 is left hanging off the end of the conduit as shown in Fig. 1 so that the carrier tube passes freely out of the end 4 and drops into a suitable basket or other receptacle.

When the carrier has thus completed its trip through the conduit, the operator at end 3 then removes cover 6 so that the system is adapted to send the carrier back in the reverse direction from end 4. When the operator at end 4 desires to send the carrier 2 back again, he inserts it into the end 4 from the bottom and applies the cover 6' of the end of the conduit in the position shown at end 3, so that air from blower 5' will blow it back through the conduit to end 3 where it is free to drop out into a suitable basket, as cover 6 is now removed.

Regardless of which way the carrier member 2 is sent, the operator at the end from which it is sent must keep the cover on to keep up the air pressure in the conduit until the carrier drops out at the receiving end. In order that the operator at the sending end may know when it arrives at the receiving end so that he may then remove his cover to put his end in condition to receive the carrier, there is provided an electrical signaling system. This comprises a suitable indicator such as a bell or a buzzer at each end of the conduit, the buzzer at one end being designated 8

and the bell at the other end being designated 8'. Each bell or buzzer is adapted to be operated from a source of electrical voltage which is ordinarily a 60-cycle supply line. This supply line is shown connected to the terminals 9 and 9A of the primary winding of a transformer T, for stepping down the voltage to an appropriate voltage for operating the buzzer. The terminals 10 and 10A of the secondary winding of the transformer are connected in series with a switch S and the buzzer terminals 11 and 11A. Thus when switch S is closed, the buzzer 8 is operated.

For the purpose of operating switch S, I provide within the conduit 1 and near the end 4 a flexible operating member 12. This comprises a flexible strip 13, for example of a thin flexible steel or bronze, fastened at its upper end to the inside of the conduit by a suitable fastening device such as the nut and bolt arrangement 14. The lower end of strip 13 extends inwardly into the conduit from the conduit wall and the strip is flexible enough so that it can readily be sprung back against the wall. There is fastened to the lower end of strip 13, for example by welding or soldering at 14a, a considerably thicker and stiffer strip 15. Strip 15 hangs downward from strip 13 inside the conduit at some distance from the inner conduit wall, for example, a quarter of an inch or so. The strip 15 is brought back against the conduit wall at the lower end of the conduit, where an L-shaped portion 17, of the strip is in contact with the inner surface of the conduit and is brought around beneath the lower end of the conduit to form a hook at 18 adapted to hook into a corresponding recess 19 formed at the end of the conduit. The recess 19 may conveniently be formed in the lower outer end of a collar member 20 placed around the lower end of conduit 1. The length of the resilient portion 13 of the strip may conveniently be in the neighborhood for example, of about five inches, and the length of the rigid portion 15 may be for example, about eighteen to twenty-four inches, the length required being determined somewhat by the speed of the carrier at the strip in the particular installation involved.

For the purpose of operating the switch, there is provided a pin 21 slidably placed within a guide 22, threaded into the collar 20 and protruding into the conduit so that the inner end of the pin extends into the conduit and the outer end of the pin protrudes toward a lever 23 mounted on the switch box.

The switch S comprises a fixed switch element 24 and a movable switch element 25, the latter being in the form of a pin attached to switch lever 23, so that when lever 23 is pressed by pin 21, the contact pin 25 will be moved into contact with switch member 24. For convenience, the switch box S is mounted in a suitable manner on a mounting member 26, which can conveniently be made of sheet metal wrapped around the conduit, just above collar 20, with the two ends 26A brought out flat and facing each other at some distance apart and bolted together by suitable bolts 27. A platform 28 is fastened in a suitable manner (not shown) to the upper edges of members 26A. On this platform is mounted a suitable bed of rubber 29 on which is mounted the buzzer 8'. The terminals 30 and 31 of switch S are connected over wires 32 and 33 to transformer terminal 10A and terminal 11 of buzzer 8 respectively, as described above, to complete the circuit from switch S to buzzer 8.

The lefthand end of conduit 1 is provided with

a switch mechanism similar to that shown at its righthand end in cross-section. Thus, the collar 20' corresponds with collar 20 and member 26' corresponds with member 26. There is similarly provided a switch S' corresponding to switch S with its resilient switch arm 23' corresponding to arm 23. Lever 23' is operated by the slidable pin 21' arranged in a manner similar to pin 21; and there is provided within this end of conduit 1 an elongated strip similar to strip 12, this strip being held at its upper end by a bolt 14' corresponding to bolt 14.

In operation, when the operator at the left end of the conduit wishes to send the carrier 2 to the right end, he inserts the carrier up into the bottom of conduit 1 while the cover is removed. Then he applies the cover 6 in the position shown in Fig. 1 and applies the compressed air so that the carrier is sent through the conduit to the receiving end. In passing the strip held by bolt 14', the switch S' will be closed, sending current from the secondary of transformer T to the buzzer 8'. This may serve a useful purpose, if it is desired to inform the person at the receiving end that the carrier is coming. Then when the carrier approaches the receiving end, it contacts strip 13 and flexes it against the inner surface of the conduit, thereby bodily moving the hanging heavier strip 15 toward the conduit wall, causing it to push pin 21 against switch lever 23. This moves switch member 25 into contact with 24, thereby closing the circuit through buzzer 8 and announcing to the sender that the carrier has been received.

The stiff strip 15, in addition to acting as an elongated switch-operating strip, serves the additional function of acting as a brake for the carrier. In a carrier system of the type described, the carrier is often traveling at a high rate of speed when it reaches the sending end, so that it tends to bounce out of the receiving basket or receptacle. By bowing the stiff strip 15 somewhat however, it lies somewhat in the path of the carrier even after the thin resilient strip 13 has been sprung against the conduit wall. The heavy strip 15 thereby tends to act as a brake for the passing carrier and slows it down to a more desirable receiving speed. The passage of the carrier may tend to straighten out strip 15 a little bit, but it is held in place at the bottom of the conduit by reason of the hook 18 which remains hooked at recess 19.

When the person at the right end desires to send the carrier back again, he inserts it in the open end of the conduit at his side, and applies the cover 6' and turns on the compressed air to send the carrier back again. In traveling back, the carrier depresses member 15 at the beginning of its trip to operate buzzer 8 and then when it reaches the other end of the conduit, it operates the member held by bolt 14' to ring buzzer 8'.

It will be recognized that by my invention, I have provided a mechanical arrangement which enables an indicating device to be operated for an appreciable length of time by a rapidly moving carrier device. The arrangement is furthermore adapted to act as a brake for the carrier if it should be moving too fast.

Although my invention has been described with particular reference to the pneumatic-pressure type of system disclosed in the detailed description, it will be understood that it can also be used with other types of carrier systems, such as the vacuum-operated type.

I claim:

1. In a pneumatic conveyor system, the combination which comprises a conduit of substantially uniform cross section, a carrier slidably fitted within the conduit, a brake in the form of a long leaf spring mounted lengthwise in the conduit with a substantial portion of its length bowed into the path of the carrier in the conduit but depressable out of the path by the sliding carrier, the spring being sufficiently strong to decelerate the sliding carrier substantially, and a switch having a contactor that is operated by the brake, the contactor being disposed behind the leaf spring in the conduit wall and movable transverse to the wall and so that the spring, on being depressed by the sliding carrier, touches the contactor for a substantial portion of the period during which the carrier is in contact with the spring.

2. In a pneumatic conveyor system, the combination which comprises a conduit of substantially uniform cross section, a carrier slidably fitted within the conduit, a brake in the form of a long leaf spring mounted lengthwise in the conduit adjacent an end thereof with a substantial portion of its length bowed into the path of the carrier in the conduit but depressable out of the path by the sliding carrier, the spring being sufficiently strong to decelerate the carrier substantially and one of its ends being free to move longitudinally in the conduit, and a switch having a contactor that is operated by the brake, the contactor being disposed behind the leaf spring adjacent the conduit wall in such position that the spring, on being depressed by the carrier, touches the contactor for a substantial portion of the period during which the carrier is in contact with the spring.

3. In a pneumatic conveyor system, the combination which comprises a conduit of substantially uniform cross section, a carrier slidably fitted within the conduit, a brake in the form of a long leaf spring mounted lengthwise in the conduit adjacent an end thereof with a substantial portion of its length bowed into the path of the carrier in the conduit but depressable out of the path by the sliding carrier, the spring being sufficiently strong to decelerate the carrier substantially, the end of the spring remote from the end of the conduit being anchored to the conduit and the other end being free to move longitudinally, and a switch having a contactor that is operated by the brake, the contactor being disposed behind the leaf spring adjacent the conduit wall in such position that the spring, on being depressed by the carrier, touches the contactor for a substantial portion of the period during which the carrier is in contact with the spring.

4. Apparatus according to claim 3 in which the end of the spring anchored to the conduit is thinner and less stiff than the balance of the spring.
